UNITED STATES PATENT OFFICE.

THOMAS J. SLOAN, OF NEW YORK, N. Y.

IMPROVEMENT IN CASTING METAL WINDOW-SASHES.

Specification forming part of Letters Patent No. 12,035, dated December 5, 1854

To all whom it may concern:

Be it known that I, THOMAS J. SLOAN, of the city, county, and State of New York, have invented a new and useful Improvement in the Method of Casting Window-Sashes, of which the following is a full, clear, and exact description, reference being had to the accompanying drawings, making part of this specification, in which—

Figure 1 is a face view of a sash cast on my improved plan as it is taken from the mold, and Figs. 2 and 3 sections thereof taken at the lines A a and B b of Fig. 1.

The same letters indicate like parts in all the figures.

It is important that the side and end rails of window-sashes, particularly the side rails, should be straight, on account of fitting the window-frames accurately.

Cast-iron sashes have long been recognized as presenting many advantages over wooden sashes; but the use of them has been much retarded on account of the difficulty of casting them with the end and side rails straight, particularly the latter. And this difficulty arises from the fact that the side and end rails are connected at given distances apart, depending on the intended size of the glass, by bars that extend from side rail to side rail and from end rail to end rail; and also from the fact that cast-iron in cooling contracts at the rate of about one-eighth of an inch to the foot. And as the form of the sash to be cast is first molded in sand, &c., it follows that as the bars connecting the rails contract in cooling they draw the rails inward, while the other portions of the length of the rails are held back by the sand or other substance of the mold, and in consequence of these two opposing forces the rails, when the sashes are taken out of the molds, are found to be bent between the points of connection with the bars, the extent of which will depend upon the distance between the connecting-bars, and somewhat upon the quality of the iron and the firmness of the mold.

The object of my invention is to avoid this defect in the making of cast-metal sashes; and to this end the nature of my invention consists in casting metal sashes with a net-work or auxiliary bars connected with the rails and between the bars for the reception of the glass, and so near together that in the process of cooling and contracting they will draw the

rails inward along their entire length to the same extent as the bars for the reception of the glass, and thus not only produce sashes with straight rails, but of greater strength than when cast in the usual way, for the auxiliary bars or net-work will take a portion of the strain, which otherwise would be sustained wholly by the main bars in the progress of contraction, and thus render them less liable to break.

In the accompanying drawings, *a a* represent the side rails of a cast-iron sash, *b b* the end rails, and *c c* and *d d* the cross and longitudinal main bars, formed with rabbets for the reception of the glass. In each open space for the reception of a pane of glass there are longitudinal and cross auxiliary bars *e e* and *f f*, and so arranged as to be in line throughout the length and breadth of the sash. The number of these auxiliary bars will depend upon the size of the space between the main bars, and they should be sufficiently numerous to insure the keeping of the rails straight in the process of contraction.

In casting sash for twelve-by-sixteen panes I have found two longitudinal and two cross bars sufficient. These auxiliary bars should be reduced in size at their junction with the rails and main bars, as represented in the drawings, so that after the casting has cooled down they can be readily cut or broken out. The thickness of metal at the junction should be just sufficient to insure the drawing in of the rails against the resistance of the mold in the process of contraction.

The proportions represented in the drawings I have found to answer a good purpose in practice.

I wish it to be distinctly understood that I do not limit myself to the number or magnitude of the auxiliary bars to be used, as these may be varied to suit circumstances, as before specified.

What I claim as my invention, and desire to secure by Letters Patent, is—

Molding and casting metallic window-sashes with auxiliary bars, substantially as herein specified, to keep the rails straight during the contraction of the metal in cooling, and then to be cut or broken out, as set forth.

THOS. J. SLOAN.
